Attorney

UNITED STATES PATENT OFFICE.

MORTIMER S. FULLER, OF LAWRENCE, MICHIGAN.

TOOL.

Application filed September 18, 1923. Serial No. 663,424.

To all whom it may concern:

Be it known that I, MORTIMER S. FULLER, a citizen of the United States, residing at Lawrence, county of Van Buren, State of Michigan, have invented certain new and useful Improvements in Tools, of which the following is a specification.

This invention relates to a tool.

My improved tool is especially designed by me for applying wire fasteners to baskets for securing the top thereto.

The main object of this invention is to provide a tool which enables the rapid and easy application of fasteners for securing basket tops by means of which the fasteners are effectively drawn to position and clinched or engaged with the cover.

Further objects, and objects pertaining to details and economies of my invention will definitely appear from the detailed description to follow.

I accomplish the objects of my invention by the devices and means described in the following specification. The invention is clearly described and pointed out in the claims.

A structure which is a preferred embodiment of my invention is clearly illustrated in the accompanying drawing forming a part of this application, in which:

Fig. I is an inside perspective view of my tool.

Fig. II is a plan view of one of the fasteners employed on the type of basket shown in Figs. III and IV.

Fig. II^A is plan view of one of the fasteners employed on the type of basket shown in Fig. V.

Fig. III is a detail fragmentary view of a basket illustrating the method of using my improved tool, the tool being here shown in its initial position.

Fig. IV is a detail view corresponding to that of Fig. III illustrating the manipulation of the tool to engage or clinch the fastener.

Fig. V is a detail view illustrating the use of the tool with a fastener of the type shown in Fig. II^A.

In the drawing similar reference numerals indicate similar parts throughout the several views.

Referring to the drawing, 1 represents a basket and 2 the top outside hoop thereof.

55 The cover comprises slats 3 mounted upon

a rim 4. The covers are secured in place by the wire fasteners 5 having hooks 6 at their lower ends adapted to be engaged under the hoop 2 and clinched over the rim 4.

It has heretofore been the general practice, so far as I am aware, to engage these fasteners with the fingers, the result being that they were not firmly engaged, permitting the covers to be easily removed, or partially removed, thereby allowing access to the contents, resulting in large quantities of fruit or the like, for which the baskets are used, being stolen in transportation.

This tool comprises a lever-like handle 7 having an inwardly curved fixed jaw 8 at its inner end. A coacting jaw 9 is secured by the pivot 10 to the knuckle 11 secured to the handle by the strap 12, the knuckle being formed on the end of the strap.

This jaw 9 is hook-shaped to be engaged under the basket hoop 2, the jaw being adapted to receive the hook 6 of the fastener 5.

In applying the fasteners they are positioned as shown in Fig. III, the hook being seated in the pivot jaw and engaged over the hoop 2. The handle is then actuated to swing the end of the fastener over the cover rim 4, the knuckle 11 constituting a fulcrum wiping the fastener over the edge 85 of the cover rim as shown in Fig. V, drawing the rim tight and at the same time clinching the end of the fastener within the rim.

To facilitate the positioning of the fasteners in the jaws, the inner faces of the jaws are preferably longitudinally grooved at 13. The end of the strap 12 is extended into a rest 14 limiting the movement of the jaw 9 toward the handle thus preventing the pinching of the operator's fingers or striking the same against the basket in adjusting the fastener and tool thereto.

In Figs. II^A and V I show a fastener 15 with a brad 16 at one end, the brad being forced into the cover top as shown in Fig. V instead of the fastener being clinched or wrapped around the rim as shown in Fig. IV, the tool being well adapted for affixing either form of fastener.

The handle 7 is preferably provided with nail puller jaws 17, thereby adapting the tool for the removal of the fasteners, and also for pulling nails and the like for opening boxes, etc.

My improved tool is very economical to produce and greatly expedites the application of fasteners of this type in an effective manner.

5 I have illustrated a simple and practical embodiment of my tool. I have not attempted to illustrate certain modifications and adaptations thereof which I contemplate, as I believe the disclosure made will enable 10 those skilled in the art to which my invention relates to embody or adapt the same as may be desired.

Having thus described my invention what I claim as new and desire to secure by Letters Patent is:

15 1. A tool for applying basket top cover fasteners comprising a lever-like handle provided with a fixed jaw, a hooked jaw adapted to be engaged with a basket hoop pivotally mounted on the inner side of said handle, the connection for said pivoted jaw to said handle comprising a knuckle adapted to constitute a fulcrum for the handle, and a rest on said handle coacting with 20 said pivoted jaw.

25 2. A tool for applying basket top cover fasteners comprising a lever-like handle provided with a fixed jaw, and a hooked jaw adapted to be engaged with a basket hoop pivotally mounted on the inner side of said handle, the connection for said pivoted jaw to said handle comprising a knuckle adapted to constitute a fulcrum for the handle.

30 3. A tool for applying basket top cover fasteners comprising a lever-like handle provided with a fixed inwardly curved jaw, and a hooked jaw adapted to be engaged with a basket hoop pivotally mounted on the inner side of said handle, the connection for said pivoted jaw to said handle comprising a knuckle adapted to constitute a fulcrum for the handle, said jaws being grooved to facilitate the positioning of the fasteners.

35 4. A tool comprising a handle provided with a fixed jaw, and a jaw pivotally mounted on said handle and adapted to receive a fastener member and to be engaged beneath the hoop of a basket, said handle being provided with a part constituting a fulcrum engaging the cover of a basket as the handle is manipulated to actuate the fixed jaw.

40 5. A tool comprising a handle provided with a fixed jaw at its inner end, a coacting jaw pivotally mounted on the inner side of

said handle, and a rest on said handle adapted to engage said fixed jaw.

6. A tool of the class described comprising a lever-like handle provided with a fastener bending jaw at its inner end, and a 60 forwardly facing hooked fastener supporting jaw pivoted on said handle in spaced relation to the said fastener bending jaw, said handle having a part in front of said pivoted jaw adapted to engage a fastener at 65 the bending point thereof.

7. A tool of the class described comprising a lever-like handle provided with a fastener bending jaw, and a forwardly facing hooked jaw adapted to be engaged with a 70 basket hoop and support a fastener thereon pivoted on said handle in spaced relation to its said fastener bending jaw, said handle having a part in front of said pivoted jaw adapted to support the fastener adjacent 75 its bending point when the handle is manipulated to apply the fastener.

8. A tool of the class described comprising a handle provided with a fastener bending jaw, and a hooked jaw adapted to be 80 engaged with a basket hoop pivotally mounted on said handle in spaced relation to said fastener bending jaw, there being a part on said handle adapted to engage a fastener at the bending point thereof and constituting 85 a fulcrum for the handle.

9. A tool of the class described comprising a handle terminating at its inner end in a fixed jaw, and a hooked jaw adapted to be 90 engaged with a basket hoop pivotally mounted on the inner side of said handle in spaced relation to said fixed jaw, said handle having a part engaging a fastener at the bending point thereof as the tool is manipulated to engage the fastener with a 95 basket cover.

10. A tool of the class described comprising a handle provided with a fastener bending jaw, and a hooked jaw adapted to support a fastener in engagement with a basket 100 hoop pivotally mounted on the inner side of said handle in spaced relation to said fastener bending jaw, said handle having a part engaging a fastener at the bending point thereof as the tool is manipulated to 105 engage the fastener with a basket cover.

In witness whereof, I have hereunto set my hand.

MORTIMER S. FULLER. [L.S.]
